E. McTOWE

ANCHORING INSERT FOR CONCRETE STRUCTURES

Filed Feb. 8, 1921

UNITED STATES PATENT OFFICE.

EDWARD McTOWE, OF ROCHESTER, NEW YORK.

ANCHORING INSERT FOR CONCRETE STRUCTURES.

Application filed February 8, 1921. Serial No. 443,445.

To all whom it may concern:

Be it known that I, EDWARD McTOWE, a citizen of the United States, and resident of Rochester, in the county of Monroe and State of New York, have invented certain new and useful Improvements in Anchoring Inserts for Concrete Structures, of which the following is a specification.

The present invention relates to anchoring

10 inserts for concrete structures and an object of the invention is to provide an insert with an elongated opening with seats on opposite sides of the opening for engagement with a headed device, the headed device being adjustable in the opening longitudinally of the latter, provision being made whereby the walls of the opening may be readily engaged with nails or projections on a mold wall, after such nails or projections have 20 been driven in the mold wall. Another object of the invention is to provide an anchoring insert having means for interlocking with pins projecting from a temporary mold wall by movement of the insert with reference to the pins in the wall, provision being made whereby the insert may be interlocked with the mold wall independently of the pins to prevent shifting of the insert with reference to the wall after the pins 25 have been interlocked with the insert.

To these and other ends the invention consists of certain parts and combinations of parts, all of which will be hereinafter described, the novel features being pointed 30 out in the appended claims.

In the drawings:

Fig. 1 is a view of the exposed face of the insert;

Fig. 2 shows the insert in a cement structure, the insert being partially in section and having a bolt anchored thereto;

Fig. 3 is a longitudinal sectional view through the insert positioned over two nails and ready for engagement with the latter;

Fig. 4 is a view similar to Fig. 3 showing the manner in which the insert is turned with reference to the nails before the latter are caused to enter the locking or retaining notches;

Fig. 5 is a part end view and part vertical sectional view showing the insert in a cement structure before the retaining wall is removed; and

Fig. 6 is a fragmentary sectional view showing the manner in which the anchoring bolt is attached to the insert.

In the building of concrete structures such as ceilings or floorings, it is customary to provide inserts in which bolts and other devices are anchored for sustaining piping, 60 shafting, or other articles or apparatus. These inserts are usually nailed to the wooden wall which is built to form the concrete structure. The concrete is then poured about the insert and permitted to harden, 65 and thereafter the wooden mold wall is removed as the nails are secured to the insert. The removal of the wall leaves the nails projecting from the concrete structure and it is then necessary to cut off the projecting ends of the nails. This consumes considerable time and labor.

A device for overcoming the foregoing objections is shown in patent granted to me on November 16, 1920, #1,359,290, in which 75 the nails are secured to the mold wall and thereafter the anchoring inserts are engaged with the nails preferably through interlocking with such nails, this interlocking being such that when the mold wall is removed from the concrete structure the nails will be disconnected from the insert so that the labor of clipping the nails is eliminated. In said patent, however, the headed device 80 engages with a slotted plate detachably connected with the insert, whereas in the present invention the opening in the insert is so formed that it may be utilized to permit the adjustment of the headed device therein, 85 while the walls thereof also serve for interlocking with the nails, provision being made by which the headed device may be readily inserted in the opening and provision also being made by which the insert may be interlocked with the mold wall independently 90 of the nails.

Referring more particularly to the drawings, 1 indicates the cement structure and 2 the mold wall. The mold wall is built up according to the common practice and nails 3 are driven through it, preferably in spaced pairs, the headed ends of the nails projecting from that face of the mold wall against which the concrete abuts. The insert is, in this instance, a cast metallic body 4 of hollow formation having an opening 5 in one wall thereof. This opening, in this instance is elongated and has its longitudinal sides converging. The sides of the body flare from said wall in which the opening 5 is provided so that the body will be suitably anchored in the concrete structure 1. The con-

verging side walls of the opening 5 are provided between their ends with notches or recesses 6. In attaching the insert to the headed projections 3 the insert is first fitted 5 over the headed projections in the manner illustrated in Fig. 3 and is then turned to bring the headed projections or nails toward the widest end of the opening 5. Thereafter, the insert is moved longitudinally 10 so as to exert pressure on opposite sides of the two nails to place them under a side tension, so that by the time the notches or recesses 6 are reached, the nails spring into such notches or recesses and hold the insert 15 against accidental displacement. It is also desirable to provide further means for securing each insert to the mold wall 2 and to this end the wall of the insert which is provided with the opening 5, may also be 20 provided with projections 7 and 7^a which, in this instance, are integral with the insert. These projections are designed for entering the mold wall 2 after the insert has been properly positioned with reference to the 25 nails 3, this result being secured by giving the insert a blow with the hammer to drive the projections 7 and 7^a into the mold wall. After the structure is built up about the 30 insert, the mold wall is removed and the nails 3 readily detach themselves from the insert with the removal of the mold wall so that it is unnecessary to perform the operation of clipping the nails from the insert as has been the practice heretofore. 35 In order to provide for attaching a headed bolt 8 or other device to the anchoring insert, one wall of the opening 5 is provided with a notch 9 and an adjacent portion of the insert is provided with a groove 10 intersecting such notch. This arrangement permits the head 11 of the bolt to be introduced sidewise into the opening 5 in the manner shown in dotted lines in Fig. 6, so that the bolt may be turned to bring the 40 head above the seats 12 formed within the insert on opposite sides of the opening 5. This construction while facilitating the passing of the head of the bolt through the opening 5, at the same time prevents the bolt 45 from becoming accidentally disconnected from the insert. After the bolt head has passed above the seats 12, it is moved longitudinally of the slot away from the notch 9, as shown in Fig. 2 of the drawings. The 50 insert interlocks with the headed projections in such a way that accidental displacement of the insert is prevented, yet it is possible to remove the nails from the insert when the mold wall is taken down. The insert is also 55 provided with pins or projections adapted to be driven into the mold wall to further prevent the accidental displacement of the in- 60

sert on the mold wall. The insert has an opening through which a bolt or other headed device may be readily inserted, this opening being so formed that it prevents the accidental passage of the head of the bolt through the opening.

What I claim as my invention and desire to secure by Letters Patent is:

1. An anchoring insert comprising a body having an elongated opening formed with converging walls for producing a lateral pressure on two spaced projections extending through said opening when the body is moved relatively to said projections, said walls being provided with notches into which said projections may spring after such movement of the body is completed and the inner face of the bottom wall on opposite sides of the elongated opening providing seats for headed devices, combined with a headed device adjustable in the opening in the direction of the length of the latter and having its head engaging the seats in any adjusted position.

2. An anchoring insert comprising a hollow body having flaring sides, and an elongated opening in its bottom wall, the inner face of the bottom wall on opposite sides of the elongated opening providing seats for a headed device, and the walls of the opening converging to provide a lateral pressure on two spaced projections extending through said opening when the body is moved relatively to the projections combined with a headed device adjustable in the opening in the direction of the length of the latter and having its head engaging the seats in any adjusted position.

3. An anchoring insert comprising a body having an opening in its bottom wall, the walls of the opening having provision to produce a lateral pressure on two spaced pins extending through the opening when the body is moved relatively to the pins, and having means for interlocking with the pins after such movement, and a projection carried by the bottom face of the insert adapted to be driven into a wall from which the pins project after the insert has been interlocked with the pins.

4. An anchoring insert comprising a body having an opening in one wall, the inner face of said wall having a seat for a bolt head about said opening, one wall of the opening having a notch, and the body wall in which the opening is provided having a groove intersecting the notch to receive the stem of a headed device as the head of the device is inserted sidewise in the opening in order to engage with the internal seat.

EDWARD McTOWE.

Certificate of Correction.

It is hereby certified that in Letters Patent No. 1,469,198, granted September 25, 1923, for an improvement in "Anchoring Inserts for Concrete Structures," the name of the patentee is erroneously written and printed as "Edward McTowe," whereas said name should have been written and printed as *Edward Mc Towe*; and that the said Letters Patent should be read with this correction therein that the same may conform to the record of the case in the Patent Office.

Signed and sealed this 23d day of October, A. D., 1923.

[SEAL.]

WM. A. KINNAN,
Acting Commissioner of Patents.
